UNITED STATES PATENT OFFICE.

ARNOLD NÜESCH, OF BASEL, SWITZERLAND.

DEFLATING PIPE FOR THE STOMACHS OF RUMINANTS.

Application filed July 8, 1921. Serial No. 483,282.

(GRANTED UNDER THE PROVISIONS OF THE ACT OF MARCH 3, 1921, 41 STAT. L., 1313.)

To all whom it may concern:

Be it known that I, ARNOLD NÜESCH, a citizen of the Republic of Switzerland, and resident of Basel, Switzerland, have invented new and useful Improvements in Deflating Pipes for the Stomachs of Ruminants (for which I have filed applications in Germany, May 2, 1914; Austria, May 1, 1915; France, April 26, 1915; Great Britain, May 1, 1915; Switzerland, August 23, 1917, and Denmark, December 9, 1919), and of which the following is a full, clear, and exact specification.

With ruminant animals (such as cattle, sheep and goats) it is customary, when there is too free a formation of gases in the first stomach, or paunch, to remove the gases collected by means of flexible tubes, which are passed down the throat into the paunch, so that the stomach gases can enter one end of the tube and issue at the other end, which projects out of the mouth of the animal.

Since, however, the entry of the throat into the paunch is at the lower part of the same, it often happens that the end of the tube inserted into the paunch buries itself in the solid food in the paunch and is thereby blocked up, so that the deflating tube does not fulfil its function, or only to an insufficient degree.

In order that the deflating tube may fulfil its function properly, it is clear that the end of the tube which enters the paunch must be in such a position that it rises into the gas-filled part above the food. In order to ensure this it has already been proposed to make the tube flexible and then to lift the end when in the paunch by external means.

This arrangement is clumsy and unsafe and leads to a complicated construction, unsuitable for this kind of tube. It is also known to make the stomach tube for human beings of separate members linked together, but in human beings, where the throat opens into the top of the stomach and the anatomical conditions are quite different from those of ruminants, the tubes are only hinged to facilitate their passage down the throat. With ruminants, however, it is necessary for the tube to be lifted in the paunch, in order to enable the gases to be drawn off.

According to the present invention, the end member of the tube is pivoted to the

flexible main body thereof eccentrically with respect to the axis of the tube and, if there is a plurality of such pivoted end members, along one and the same generating line of the tube, the adjacent terminal portions of said parts of the tube are so shaped as to allow of pivotal movement of said end member (or members) out of the axis only in a direction opposite to the pivot connection side. In this manner the end member (or members) of the deflating tube is automatically lifted in the paunch, since, if the tube is inserted with the pivots on the under side, the end member (or members) of the tube, on striking an obstruction in the paunch, is automatically turned upwards owing to a turning moment relatively to the pivot.

The invention is illustrated in the accompanying drawings by way of example, Fig. 1 showing a deflating tube in use on a cow; Fig. 2 showing the tube broken into three sections.

The deflating tube according to the present invention consists of a rigid handle *a*, a flexible central part or main body *b* which cannot, however, rotate on itself, and a similar terminal part *c* to which two rigid end members *d*, *f* are freely pivoted. Of these two the end member *d* is pivoted to a terminal on the part *c*, and the end member *f* is pivoted to the member *d*, in such a manner that the pivots are eccentric to the axis but in the same generating line of the tube. On one side of the connection pivots, the end members *d* and *f* are provided with an abutting face or stop indicated at *h* in Fig. 2, so as to be prevented from overturning downwards out of the straight line; however, said abutting or stopping means could also be provided at any other convenient point. On the opposite or upper side, the said end members are bevelled at *i* (Fig. 2) so that they can be inclined to the side or turned upwards with respect to the axis of the tube. This change of direction of the members *d*, *f* occurs automatically on inserting the tube in the paunch. When inserting the tube, care must be taken that the pivots are underneath. If these members strike against an obstruction in the paunch, they automatically turn upwards as shown in Fig. 1, and the member *f* finally assumes an upright position, in which it allows the stomach gases to pass off through the opening *g* in the tube and so pass out through the tube.

The flexible part of the tube consists, in

the construction shown, of a comparatively stiff spirally wound steel strip, but it may also be constructed in other ways. The front pivot member *f* is smoothly rounded off at its free end, in order to prevent any injury to the internal organs. The various parts of the throat tube are screwed together in the usual manner, so that the tube can be taken apart for transport purposes. The sections may, however, be connected together in any other manner. If necessary, the openings at the pivots may be covered over and the parts may be pivoted together by pliable connecting parts instead of by ordinary hinges, but these parts must always lie in the same generating line. The flexible part of the throat tube may be made of metallic tubing pressed flat.

What I claim is:—

A deflating tube for the stomachs of ruminants, consisting of a rigid section, a flexible section secured thereto, and a third section secured to said flexible section, consisting of a plurality of portions pivoted to each other in such manner as to permit pivotal movement of said portions in only one direction with respect to the common longitudinal axis of the three sections.

In witness whereof I have hereunto signed my name this 16th day of June, 1921, in the presence of two subscribing witnesses.

ARNOLD NÜESCH.
